CLAIM

The ornamental design for a combined canister and flower arrangement container, as shown and described.

DESCRIPTION

FIG. 1 is a top perspective view of a combined canister and flower arrangement container showing my new design;

FIG. 2 is a top perspective view thereof with the lid in position as a pedestal;

FIG. 3 is a top plan view of FIG. 1;

FIG. 4 is a cross-sectional view thereof on an enlarged scale taken on line 4—4 of FIG. 3;

FIG. 5 is a side elevational view of FIG. 1 on an enlarged scale;

FIG. 6 is a bottom plan view of FIG. 5; and

FIG. 7 is a side elevational view of FIG. 2 on an enlarged scale.

FIG. 1
